United States Patent Office

Des. 182,532
Patented Apr. 15, 1958

182,532

CANISTER FOR COOKIES

Elwood A. Neese, West Bend, Wis., assignor to West Bend Aluminum Co., West Bend, Wis., a corporation of Wisconsin

Application February 27, 1956, Serial No. 40,346

Term of patent 14 years

(Cl. D44—6)

The figure is a view in side elevation of a canister for cookies embodying my new design.

The dominant features of my design reside in the portions shown in full lines.

I claim:

The ornamental design for a canister for cookies, substantially as shown and described.
